METHOD OF TREATING OILS

Application filed September 5, 1928. Serial No. 304,090.

This invention relates to a method of treating animal, vegetable, marine or mineral oils for purifying, decolorizing and brightening such oils. The invention particularly relates 5 to a method of removing cloudiness from oil, and in rendering such oil bright and clear, not only at high temperatures, but also at any predetermined low temperature. The invention also relates to a continuous method 10 of treating oils with adsorbents and in treating the oil during such process of decolorization and purification with adsorbents so that the finished product is clear and bright at low temperatures.

15 In treating oils such, as, for example, mineral oils, with adsorbents such as fuller's earth, finely divided decolorizing clays, acid treated clays, or other adsorbents, it is customary to mix the oil to be treated with the adsorbent, heat the mixture if so desired, and then remove, or separate, the oil from the adsorbent. The word "adsorbent" as used herein includes all decolorizing agents such 20 as those listed above, and any others of similar nature and action, and the word "adsorption" refers to the action of such decolorizing agents on the oil.

25 In the manufacture of lubricating oils and other mineral oil, it has been found that even though the oil treated with an adsorbent is clear and bright at the relatively high temperatures used during the adsorption step proper, such oils after having been separated 30 from the adsorbent and cooled, generally become cloudy.

35 It has been discovered that the clouding of various oils, upon being reduced in temperature, is caused by the presence of suspended 40 and dissolved moisture in the oil. The solubility of water in the oil increases with increasing temperatures so that oils which may be bright at elevated temperatures, but which are saturated with water at that temperature, 45 cloud upon cooling by reason of precipitation

from solution of minute water drops throughout the oil.

An object of this invention is to disclose and provide a method whereby oils may be rendered bright and clear at any predetermined low temperature. 50

Another object of this invention is to provide a simple and effective method of removing cloudiness from oils.

An object of this invention is to disclose and provide a method of treating mineral oils whereby the oils may be steam-sweetened and rendered bright and clear when cooled to any predetermined low temperature. 55

Another object of this invention is to provide a method whereby oils may be treated with adsorbents, sweetened and brightened in a continuous manner. 60

Other objects and advantages of this invention will be apparent from the following 65 detailed description of one preferred method of carrying out the invention and the particular sequence and character of steps embraced in the body, it being understood that the invention is not limited to the preferred 70 method described in detail but embraces various modifications and alternative steps or operations, some of which are hereinafter described, such alternative steps or methods being apparent to those skilled in the art after 75 considering the disclosures made herein.

For purposes of illustration, reference shall be made to the appended diagrammatic illustration of a complete process for treating oils, and particularly mineral oils, with an 80 adsorbent and for sweetening and brightening the oil.

The apparatus for carrying out the invention may comprise, as illustrated in the drawing, a mixing tank 1, preferably provided 85 with a conical bottom 2, and a valved discharge line 3 leading from the lower portion of the tank 1 to a circulating pump 4. The tank 1 may be supplied with oil to be treated from a suitable source (not shown) by means 90

of a valved feed line 5. Adsorbents may be supplied to tank 1 in any suitable manner and in any suitable form, for example, in dry, finely divided condition, or in the form of a 5 thick oil-adsorbent or water-adsorbent suspension, mud, or slime. For purposes of illustration, adsorbent may be supplied to tank 1 from a hopper, or tank, 6, provided with a suitable controllable outlet. A suitable mixing 10 device may be provided in tank 1.

The discharge line 7 may be provided with a by-pass line 8 and valve 9 whereby all, or a portion, of the oil discharged by the pump 4 may be returned to tank 1 for circulating, 15 mixing, or other purposes. The main pipe line 7 is provided with a valve 10, preferably leading to a feed pump 11, then leads to a heat exchanger 12 in which the oil, or mixture of oil and adsorbent, may be preheated. 20 From the heat exchanger 12, the oil-adsorbent mixture may be carried by line 13 to a heater of any desirable construction and size such, for example, as a heater 14 provided with a bank of tubes 15 and a combustion zone 16.

25 The oil-adsorbent mixture, after passing through the bank of tubes 15, may be discharged by line 17 into a steam separator 18 provided with a valved vapor outlet 19. The mixture of oil and adsorbent may then be 30 turned by a line 20 from the steam separator 18 to a second bank of tubes 21 in the heater 14 (or to a separate heater if desired), and, after being raised in temperature to the desired degree, discharged therefrom by a line 35 22 through the heat exchanger 12, and by a line 23 into a suitable brightening, steam-sweetening, or other, apparatus.

In the form of apparatus shown in the drawing, the mixture of oil and adsorbent is 40 discharged by line 23 into the upper portion of a combined sweetener and brightener 24, which may take the form of a vertical cylindrical tank provided with centrally disposed conical distribution plates 25, and alternate 45 annular plates 26. Means, 27, for introducing steam or substantially inert gas, from a valved supply line 28 into the brightener 24, may be provided. Vapors from the brightener 24 may be discharged into a dephlegmating 50 or refluxing zone or chamber 29 provided with a cooler, 30, supplied with cooling fluid. A vapor discharge line 31 from the dephlegmating chamber 29 may lead to suitable condensers and vacuum pumps, 55 which are not shown.

The oil discharged from the lower portion of the brightener 24 may be carried by line 32 to a booster pump 33, and forced thereby through line 34, through a heat exchanger 35 and line 36 into a suitable separating mechanism such as a filter 37. The oil from filter 37, discharged through line 38, may then be passed through a cooler such as the heat interchanger 39, and discharged therefrom by 60 line 40 to storage, or further treatment. The

heat interchangers 35 and 39 may be supplied with water, or other fluid, so as to establish flow of cooling liquid therethrough counter to the flow of oil through such coolers. Supply line 41, line 42, and discharge line 43 indicate means for passing cooling fluid through the coolers 35 and 39. 70

The operation of the process in the above described apparatus will now be described.

Oil to be treated may be introduced to the 75 mixing tank 1, either continuously or intermittently, but preferably in a continuous manner, and mixed therein with a suitable adsorbent, such as a decolorizing and adsorbing clay, supplied to the tank 1 from tank 80 or hopper 6. The condition and the quantity of the adsorbent, added to the oil, may differ materially, depending upon operating conditions, type of oil, the effect desired, and other considerations. The mixture of oil and adsorbent is then sent through heat exchanger 12 where its temperature may be raised to 150 to 400° F. The mixture may then be sent through the heater 14, and particularly, bank 85 of tubes 15, where it is raised in temperature 90 to above 250° F.

If the heat exchanger 12 is capable of raising the mixture of oil and adsorbent to a temperature above 250° F. then it may not be necessary to use a portion of the heater 14 95 or the tubes 15, and such passage of the oil-adsorbent mixture through the bank of tubes 15 can be eliminated.

The heated mixture of oil and adsorbent 100 may then be passed into a separator 18, preferably maintained at a super-atmospheric pressure, and the major portion of water mechanically held in the oil (in suspension in the oil) and some of the water held by the adsorbent is released and removed from the mixture of oil and adsorbent in the form of steam or vapor. The partly dehydrated oil may then be brought up to a desired adsorption, or contact temperature, by passing the oil 105 through a heater, say the bank of tubes 21 in heater 14. When lubricating oils are being treated, the temperature of the oil-adsorbent mixture discharged from bank 21 by line 22 may be from about 450° F. to about 110 750° F., although temperatures appreciably differing from this range may be used under certain conditions. The oil may then be cooled somewhat by passage through the heat exchanger 12 where its heat is transferred in part to the incoming mixture; the use of such 115 cooling step, and of the heat exchanger 12, may be dispensed with under certain conditions, for example, where the oil discharged from bank 21 is not at a very high temperature. 120

The oil at this stage of the process has been 125 decolorized and treated by the adsorbent and if the adsorbent were to be separated from the oil at this stage, the oil would be clear and bright at the temperatures existing 130

(from about 275 to 475° F.), but upon cooling, the separated oil would become cloudy or foggy by reason of water precipitating from solution in oil.

- 5 In order to produce an oil which will remain clear and bright at low temperatures, the mixture of oil and adsorbent discharged from line 23 is then treated to remove a major portion of water dissolved and suspended in the oil. The greater portion of suspended water was removed in separator 18 but an excessive quantity of dissolved water is present in the oil, it being remembered that the solubility of water in oil increases 10 with temperature. The water content of the oil should be reduced to below the saturation content corresponding to any predetermined lower temperature, say 80° F., 40° F., or even lower.
- 20 This reduction may be accomplished at any temperature between the maximum and minimum temperatures of the operating cycle (between 150° and 750° F., as stated hereinabove), but it is preferably carried out 25 at a sufficiently elevated temperature to insure a reasonably high vapor pressure of the water (as above 250° F.), but at a low enough temperature to prevent substantial vaporization of the oil, unless it is desired to also remove the light products of cracking often 30 created during the contacting period at high temperatures. The latter object, removal of cracked constituents, may be accomplished separately as by steam-blowing the oil after 35 contact with adsorbent, but before brightening by removal of water in solution.

The brightening operation may, in accordance with our invention, be preferably accomplished by the use of vacuum, although it 40 may be accomplished by any means for reducing the partial pressure of the water vapor below the vapor pressure of the water in solution, as by blowing with air, inert gas such as carbon dioxide, or application of 45 vacuum. If the separator 18 is maintained at super-atmospheric pressure (as noted above) then the oil in line 23 will be under pressure and at a high temperature, and such oil entering brightener 24 will have its pressure materially reduced, thus facilitating 50 vaporization of contained water, even though the brightener 24 is not maintained under vacuum. Furthermore, the brightening operation can also be carried out by cooling 55 the oil to a low temperature so as to precipitate the water from the solution, and then filtering, the adsorbent being removed either at that time or by a preceding filtration. The latter filtration method is not particularly desirable, however, and the process 60 will be described as carried out by the application of vacuum in conjunction with a sweetening operation to remove odors and light constituents resulting from a high temperature contacting. Blowing with air is

somewhat undesirable for some oils owing to a chemical action of the oxygen upon the hot oil. Blowing with inert gases is slightly more expensive owing to the cost of supplying the inert gas and of dehydrating and preparing the wet gas for recirculation. 70

In operating by the use of the apparatus disclosed in the drawing, the mixture of oil and adsorbent is discharged into a vacuum tank or brightener 24, preferably equipped with suitable baffle plates or the like so that a large surface area of the mixture of adsorbent and oil is exposed. Steam may be supplied to the lower portion of the brightener 24 for sweetening purposes so as to remove odoriferous constituents created during a high temperature contacting in the bank of tubes 21 of heater 14. 75

The brightener 24 is maintained under a suitable vacuum, the degree of vacuum depending upon the temperature of the mixture of oil and adsorbent being supplied to the brightener and upon the degree to which the water content of the oil must be reduced. The water is removed from solution in the oil and discharged from the brightener 24 into a dephlegmator 29 wherein petroleum oil constituents vaporized during this operation may be recondensed and return to the brightener 24. 80

The steam, undesirable constituents resulting from the effect of the adsorbent upon the oil, and the water vapors, pass through the dephlegmator 29 and are discharged through the vapor outlet 31 which leads to suitable condensers and vacuum pumps utilized in maintaining a desired vacuum upon the brightener. The oil, after such sweetening and brightening process, may then be immediately filtered, or otherwise treated, so as to separate the adsorbent therefrom, or as shown in the drawing, the oil may be first cooled partially, then filtered and then cooled to a sufficiently low temperature to enable it to be sent to storage. 95

This invention is not to be limited to a process such as is described in detail hereinabove, it being understood that numerous changes and modifications may be made without departing from the invention. It is to be distinctly understood, for example, that the brightening operation need not be carried out in conjunction with a sweetening operation as numerous oils may not need a sweetening operation to be performed thereon. Furthermore, the process is not to be limited to the exact sequence or steps of operations described as the particular process hereinabove described is merely illustrative of a complete contacting process of treating oils in which the brightening operation forms a single step. For example, the oil may be treated with an adsorbent, the adsorbent removed, and the water content of the oil then reduced to below the saturation content of 100

water which would exist in the oil at a predetermined low temperature.

Obviously the brightening process may be made a part of numerous other processes of treating oil where it is desired to produce a clear, bright oil which will remain clear when cooled to a low temperature. The removal of dissolved water from the oil need only be carried out to a sufficient extent to reduce the water content below saturation conditions at a predetermined low temperature.

We claim:

1. In a process of producing bright oils, the steps of mixing an oil to be treated with an adsorbent, heating the mixture under pressure, partially releasing the pressure on said heated oil mixture to permit vaporization of a portion of water contained in said mixture, removing such vaporized water, again heating said mixture to above 250° F., and reducing the water content of the heated oil to below the saturation content of water which would exist in said oil at a predetermined low temperature by reducing the pressure to subatmospheric to reduce the partial pressure of the water vapor below the vapor tension of the water in solution in the oil being treated.

2. In a process of producing bright oils, the steps of mixing an oil with an adsorbent, heating the mixture to above 250° F. under pressure, partially releasing the pressure on said heated oil mixture to permit vaporization of a portion of water contained in said mixture, removing such vaporized water, again heating said mixture to above 250° F., then subjecting the mixture of oil and adsorbent to subatmospheric pressure to reduce the water content of the oil to below the water content which would exist in said oil at saturation condition at a predetermined low pressure, and finally separating the adsorbent from the treated oil and cooling the oil.

45 Signed at El Segundo, California, this 22nd day of August, 1928.
